[57] **CLAIM**

The ornamental design for an air conditioner cord warning label, as shown and described.

DESCRIPTION

FIG. 1 is a front elevational view of an air conditioner cord warning label showing our new design; and,

FIG. 2 is a rear elevational view of the air conditioner cord warning label.

The label has no substantial thickness and is black and white as shown in the Figures with the exception of the stippled areas which are solidly colored Safety Orange as defined by the American National Standard ANSI Z335.1-1991.
